UNITED STATES PATENT OFFICE.

ADOLPH Y. S. ALBUM, OF CHICAGO, ILLINOIS.

BOTTLE STOPPER.

Application filed September 22, 1925. Serial No. 57,893.

The present invention relates to improvements in bottle stoppers as shown in my application, filed September 11, 1922, Ser. No. 587,490, which has matured into Patent 5 No. 1,504,664.

It is the object of the invention to improve bottle stoppers or caps of the milk bottle type, having integral pull-tabs so that they will form a tight seal with mouth of the 10 bottle at the point adjacent of the pull-tab.

The invention resides in the sundry detailed construction, and in the combination and arrangement of parts which will be pointed out in detail as the description of 15 the invention proceeds.

In this specification and the annexed drawings, the invention is disclosed in the form in which it is considered to be the best, but the invention is not limited to such 20 form because it is capable of being embodied in other forms; and it is to be understood that in and by the claims following the description herein it is intended to cover the invention in whatever form it may embody 25 within the scope thereof.

In the drawings which disclose the preferred embodiment of the invention as at present devised:—

Figure 1 is a plain view of cap constructed 30 in accordance with the invention.

Figure 2 is an edge view of the cap in Figure 1.

Figure 3 is a plan view of another form 35 of the invention.

Fig. 4 is a plan view of a modified form 40 of the invention,

Fig. 5 is an edge view of the cap shown in Fig. 4, and

Figs. 6, 7 and 8 are other modified forms 45 of the invention.

In carrying my invention into practice a relatively thin flat plate-like body 1 may be 50 of any desired outline or shape and made of any suitable material such as wood, pulp, strawboard or the like, and coated or otherwise impregnated with a waterproof material, such as paraffin or the like.

The stopper or cap thus provided is of such dimensions as to tightly fit in the mouth of a bottle with which it is used. In the form of the invention herein shown, the caps are illustrated as being a disk formation provided with an integral tab 2 extending outwardly from the peripheral edge 55 of the cap, the tab being of any suitable

shape or formation. The tab may be scored, notched or depressed to form a definite groove or incision 3 extending in a direction substantially transversely of the tab at a point to one side of the line *a* forming a continuation of the peripheral edge of the cap. The construction thus far recited is covered by my Patent No. 1,435,443, above referred to, and forms no part of the present invention and may not be used. 60

This invention further resides in scoring, notching, grooving or depressing the cap along the line at a point adjacent the tab 2, but within the peripheral edge of the cap body, the scoring, notching or grooving 70 forming a chord of the cap body. The purpose of so grooving or notching the cap, adjacent the pull-tab 2, is to weaken the cap body at this point permitting the cap to function in a peculiar manner which is of 75 advantage when using a cap having pull-tabs.

In Figure 1, the scoring 4 extends across the cap substantially parallel with its periphery and adjacent the tab for a distance 80 at least the width of the tab, and has its end portions 4^a extending at an angle therefrom to the peripheral edge of the cap on opposite sides of the tab. This construction permits of a peculiar flexing or disposition of 85 the stock at the juncture of the tab with the cap so as to make a very tight fit in the rabbet of the bottle mouth preventing leakage at that point; and, further, has the function of facilitating the removal of the cap, when 90 the tab 2 is pulled, by permitting flexure of the cap at the point of scoring, under the pulling strain, thus reducing the liability of tab being torn off.

The cap shown in Fig. 3 shows the scoring 4^b, which corresponds to the scoring 4 in Fig. 1, as arcuate with the medial portion thereof opposite the tab 2^a extending parallel with periphery edge of the cap, if continual, through the juncture of the tab and 100 cap. The end portions of the scoring 4^b extend to points adjacent the peripheral edge of the cap, as shown, because of the scoring 4^b being on a greater arc, or, in other words having a greater radii, than periphery of the 105 cap.

The scoring 4 and 4^b may be provided on either or both faces of the cap.

Figs. 4 and 5 show the cap scored or stamped, as at 5, to have a circular marginal 110

portion and having the scoring 6 extending on a substantial chord of the cap adjacent and opposite the pull-tab 2^c.

In Figs. 4, 6, 7 and 8, other forms of scoring the body of cap are shown.

Throughout the specification and claims, the words scoring, grooving, depressing, notching and incisions are used without distinction, and refers to any means by which 10 the cap may be weakened at the points indicated. While I have shown various forms and manners for weakening the cap at the points desired, it is to be understood that any other form, style or manner of weakening 15 the cap at these points is within the purview and scope of this invention.

What is claimed as new is:—

1. A bottle cap comprising a disk-like body having an integral outward extension 20 at its periphery, scoring on the cap adjacent

and opposite the extension with its end portions extending toward and at an angle to the periphery of the cap.

2. A bottle cap comprising a disk-like body having an integral outward extension at its 25 peripheral edge, scoring on the cap adjacent and opposite the extension with its end portions extending at an angle to the periphery of the cap, beyond the opposite sides of the tab and in the direction of said edge. 30

3. A bottle cap comprising a disk-like body having an integral outwardly extending tab at its peripheral edge, scoring on the cap adjacent and opposite the tab and extending out of parallel with said peripheral edge 35 with its termini turned toward said peripheral edge.

In testimony whereof I have hereunto set my hand.

ADOLPH Y. S. ALBUM.
